UNITED STATES PATENT OFFICE.

JOHN TONGE, OF ROCHDALE, COUNTY OF LANCASTER, ENGLAND.

FIRE-EXTINGUISHER.

SPECIFICATION forming part of Letters Patent No. 363,187, dated May 17, 1887.

Application filed December 23, 1886. Serial No. 222,418. (No model.)

To all whom it may concern:

Be it known that I, JOHN TONGE, a subject of the Queen of Great Britain, residing at Henry street, Rochdale, in the county of Lancaster, England, have invented a new and useful Fire Extinguisher or Sprinkler, of which the following is a specification.

My invention relates to fire-extinguishers—better known as “sprinklers”—used in works, 10 manufactoryes, or other places, and applied at such parts thereof as may be subject to the ravages of fire or conflagration, and is so adapted and arranged as to operate in an automatic manner, being affected by the aid of 15 the expansive properties of a liquid or liquids in such a manner that, upon the origination of fire in the place or places wherein one or more of my apparatus is or are provided, the heat which may be due to the fire or conflagration 20 causes my apparatus to operate, and to discharge water therein and at convenient parts thereof.

An important feature of my invention consists in an effective control of the water-discharge, especially at the time when the fire or 25 conflagration has been put out. At such a time the apparatus is caused to reverse itself and the discharge of water is discontinued, thus avoiding any unnecessary damage to machinery or goods by water, which, as is well 30 known, often results in loss or damage thereto quite as great and as serious as loss or damage caused by fire.

My invention provides an automatic device, 35 its action being governed by the dilution of fluids produced by an increased temperature, such fluids only being employed for this purpose as will expand and contract with an increase and decrease of temperature above and 40 below the normal point. I provide, therefore, by my invention a fire-detector, as well as a fire-extinguisher, whereby fire in the immediate neighborhood will be at once and automatically extinguished, even before it could 45 be certainly detected by the usual means.

In order that my invention may be well understood, I have reference to the accompanying sheet of drawings, which fully illustrate my invention, wherein like letters of 50 reference indicate like parts.

Figure 1 is a side elevation in section, showing the position of apparatus when closed or

in equilibrium. Fig. 2 is a side elevation, part in section, showing position of apparatus when in operation. Fig. 3 is an end view. 55 Fig. 4 is a plan.

My invention consists of what I will term, for convenience of description, “a liquid-containing vessel” A, of metal or other suitable material as may be necessary. I preferably 60 employ materials being good conductors of heat. When metal is employed, I construct the vessel A of copper, which may, if desired, be provided in the interior with a lining of earthenware or covered with a solution of any 65 suitable composition, so as to obtain an enameled, hardened, or impenetrable surface, in order to resist the corrosive action of certain liquids. The said vessel may be of spherical or any other desired form. By preference I 70 adopt the form as shown and illustrated in the drawings herein, as the vessel affords a small capacity for the storage of a liquid. I supply the vessel A with a liquid of a volatile nature, which may be benzoline, or any other suitable hydrocarbon or spirituous fluid or sulphurous acid. 75 In a case where the fluid by contact may be injurious to the rubber cover B, situated at the upper part of the vessel A, I interpose oil in a convenient space between the under side of 80 the cover and the surface of the liquid contained in the vessel. By such means the cover B maintains its pliable or elastic quality.

On the upper side of the cover B is situated a separate attachment, D, having a chamber, 85 C, which lies just over the cover B, and which is filled with glycerine, linseed or other oil, or any heavy-bodied liquid. This liquid extends into the tubular portion of the attachment D and is in contact with the under side 90 of a piston, F, which may move vertically in the tubular portion E of the attachment D. The piston F is provided with suitable leather or rubber packing, consisting of a screw-threaded piece, G, and a leather or rubber ring, H. The upperside or part of the piston F, which projects into a tubular attachment D', which also furnishes a support for the part D and its appendages, is in contact with the under side of a graduated lever, J, which is 95 provided with a movable weight or counterpoise, K. The weight K is situated in any convenient position on the graduated lever J, so as to equalize or counterbalance a pressure 100

of water passing through the tube or pipe L, and to maintain a position of rest or equilibrium at any temperature, being the normal temperature of the place wherein the apparatus is situated. The functions of the lever J are to respectively open and close a communication between the water-way L, which is the source through which the water is allowed to pass, and the rose or jet M, accordingly as it is actuated by the piston F. The jet M may be of any form and contain any number of suitable perforations, as may be desired, and may extend in any direction or terminate at any distance from the water source or supply passing through L.

I will now proceed to describe the mechanism which controls the delivery of water through the rose or jet M, such mechanism being in conjunction with the lever J. The lever J is held in position and supported by a pin or pivot, N, upon which it is free to turn or oscillate. One extremity of the lever J (that is, the extremity or end opposite the weighted end) conveniently engages with a piston, O; and, as shown in the drawings herewith, the lever enters into a slot or recess, P, of the said piston, the piston O being free to slide or move in the vertical tubular branch piece R, which has a fixed or stationary position. At the lower part of the piston is provided a spindle, S, having at its lower part a valve, T, which valve closes the opening U. The piston being provided at its lower part (being the upper part of the spindle S) with proper packing to insure efficiency in working, the lower part of the stationary branch piece is provided with the rose or jet M. At any convenient part of the under side of the liquid-containing vessel A, I affix a vessel or receptacle, W, in which I place or provide a suitable spirituous liquid or combustible substance, such liquid or substance being connected or in communication with a fuse, X, leading from said vessel W to any point or points where goods or combustible articles are stored.

My apparatus may be connected or applied at the part Z of the branch pipe R to any pipe or tube conveying water at high or low pressures. Any number may be applied and used, being fixed or situated and carried by a support, D', at the upper part of a room or place which is desired to be insured against damage by fire, or fixed in any other convenient position, as may be found convenient with relation to machinery or goods.

In the event of an increase of temperature in the neighborhood of my apparatus, which may be caused by a fire, at such a time the volatile fluid contained in the vessel A will consequently become dilated or expanded, and will actuate or press upward the rubber cover B, and compress or force the glycerine or heavy-bodied substance against the lower part of the piston F. Manifestly upon such occurrence the lever J will be actuated, and thus

raised to the position as shown in Fig. 2. The lever then actuates the mechanism contained in the vertical tubular part of the branch pipe R. The valve T at the lower part of the spindle S then assumes the position as shown in Fig. 2, and thus water is allowed to pass from the water-way L into the rose or jet chamber L', and thence through the perforations Z', in the form of a finely-divided spray, issuing therefrom with more or less force, accordingly as more or less perforations are provided therein and accordingly as the water passing through the same is of high or low pressure.

By means of fuse X combustion is communicated from the point where fire occurs to the volatile and combustible fluid in vessel W, whereby the expansion of the fluid in vessel A is greatly hastened and the action of the lever J thereby precipitated. It should be clearly understood, however, that the action of the fire-extinguisher, while it may be hastened by, is not dependent upon, the ignition of the fluid in vessel W.

Upon the decrease of temperature in the neighborhood of my apparatus, which may be due to the fact of the flames having been extinguished, the liquid contained in the vessel A will become contracted. Consequently the piston F will fall or lower its position. Thus the normal position of the piston O will be restored. (See Fig. 1.) The water under such circumstances will then cease to flow through the jet M. Thus unnecessary damage caused by water will be obviated, which is as serious as loss or damage caused by the ravages of fire.

In conclusion, I would have it clearly understood that I do not, and it will be inferred from the foregoing description that I cannot, bind myself to the exact details as herein shown, as it may be and will be necessary to depart from the details of my invention without deviating from the principle thereof.

I am aware that prior to my invention sprinklers or fire-extinguishers have been made by means of which water has passed therefrom in the form of jets or sprays; but I am not aware that any of such sprinklers operate in an automatic manner by the aid of the expansive properties of liquids.

It will be seen that after the expansion of liquid has once taken place and operated the lever J, the escape of water will continue until the fluid in vessel A has so far contracted as to permit the valve T to seat. This contraction will not take place until the normal temperature is restored to the surrounding atmosphere.

Therefore, what I do claim as my invention, and desire to secure by Letters Patent, is—

1. In an automatic fire-extinguisher, the combination, with the water-way and a valve closing the same, of a weighted valve-lever actuating the valve, a piston bearing against said lever, an expansible fluid acting on the piston, a vessel containing a combustible fluid, and one or more fuses leading from a distant

point or points to said vessel, the latter being arranged beneath the vessel containing the expansible fluid, substantially as described.

2. The combination, with the water-way, of 5 a distributor having valve T, a weighted lever, J, actuating the valve, a piston, F, operating the lever, a heavy fluid bearing against the piston, a vessel, A, containing an expansible fluid beneath a flexible diaphragm, on

which the heavy fluid rests, a vessel, W, containing an inflammable fluid arranged beneath vessel A, and one or more fuses, X, leading from a distant point or points to said vessel, substantially as described.

JOHN TONGE.
